CLAIM

The ornamental design for a splash sprinkler, as shown and described.

DESCRIPTION

FIG. 1 is a perspective view of a splash sprinkler showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The broken lines throughout the drawing figures and all areas between the broken lines adjacent to the circular solid lines in FIGS. 7 and 8 depict portions of the splash sprinkler that form no part of the claimed design.

The oblique shading lines in the drawings are included to denote the reflective quality of surface planes on the splash sprinkler.
